Attorney.

UNITED STATES PATENT OFFICE.

ALBERTO I. WOODRING, OF WATERLOO, IOWA, ASSIGNOR TO THE A. I. WOODRING COMPANY, OF WATERLOO, IOWA.

SIGNAL-GOVERNING APPARATUS.

1,417,124.

Specification of Letters Patent. Patented May 23, 1922.

Application filed December 8, 1921. Serial No. 520,918.

To all whom it may concern:

Be it known that I, ALBERTO I. WOODRING, a citizen of the United States of America, and a resident of Waterloo, Blackhawk County, Iowa, have invented certain new and useful Improvements in Signal-Governing Apparatus, of which the following is a specification.

My invention relates to improvements in signal governing apparatus, and the object 10 of my improvement is to provide mechanism for operating said apparatus in a predetermined timing of successive actuations and intervals, manually, incorporating with said 15 mechanism power-relaying means for adding effective power impulses in the said actuations, with automatic resetting of the mechanism.

My said improvement also is an improvement 20 upon the means and apparatus shown in my co-pending application for patent Serial Number 481,986, filed July 1, 1921.

The above object has been accomplished 25 by the means which are specifically shown in the accompanying drawings, but it is to be understood that changes in the precise embodiment of invention herein disclosed can be made within the scope of what is 30 claimed without departing from the spirit of the invention.

In the drawings, Fig. 1 is an elevation of 35 my improved mechanism operatively connected to a whistle signal, and Fig. 2 is an elevation, in partial section, of parts there- 40 of, taken at an angle of ninety degrees to said Fig. 1. Fig. 3 is an enlarged and longitudinally sectioned view of the power cylinder with movable enclosed elements in elevation, and parts broken away.

Like numerals of reference designate like parts therein.

As in my previously filed application above, this invention is particularly appropriated for actuating the whistle 1 of a locomotive in a predetermined timing of actuations and their intervals while giving an audible signal in approaching a highway crossing. This signal may comprise any desired number of such actuations and timing, but the embodiment shown illustrates 50 means for giving four successive blasts of the whistle under the accepted code, wherein this signal comprises a two second blast, an interval of one second, another two second blast, a one second interval, a one sec-

ond blast, a one second interval, and a final one second blast.

My device is capable of being set for automatic actuation and re-setting, by a single manual action of the engineer, so that his 60 attention is not diverted from other necessary or simultaneous duties, and thus the whistle signal may be given in the prescribed manner without any deviation or irregularity. 65

Furthermore, the incorporation with this device of a power-relaying means, renders the manual power required for the initial action very light, not burdensome, while the signal is by the intervention of said power-relaying means actuated positively, quickly 70 and strongly.

Referring now to the drawings, the numeral 29 denotes a spring-barrel containing a spiral spring 31, one end connected thereto and the other end of the spring being secured to a rock-shaft 20 mounted centrally in and projecting from said barrel. The barrel 29 is fixed rigidly on the lower end of a hanger 27. One end of the shaft 20 extends beyond the barrel and has a crank-connection with a plunger in a dash-pot 30, said crank-connection and plunger not being shown. On the other end of said shaft is fixed a disk 19, and a cord 25 has one end 75 secured on the circumference of said disk to wind partially around it, and has a terminal pull-handle 26 for the use of the engineer. On the opposite part of the circumferential edge of said disk are spaced projections 24, 23, 22 and 21, whose marginal lengths as 80 also the lengths of their intervals are such as to correspond relatively to the successive and differential timing of whistle blasts and intervals above described. 85

The numeral 11 denotes a fixed arm extending from the hanger 27 horizontally and is bifurcated at its outer end. A vertically-disposed lever 13 is medially pivoted on a pintle 14 fixed across said bifurcations. A 100 tappet or finger 17 is pivoted at 16 on the lower end of said lever to project at a right angle therefrom toward and in the plane of said disk 19, and has an anti-friction or traveler wheel or roller 18 pivotally mounted on its outer end to travel upon the circumferential edge of the disk. The other end of the finger 17 engages a shoulder 42 105 on said lever to limit its movement in one direction. 110

The numeral 32 denotes a closed end cylinder supported by means of a bracket on said hanger 27. The cylinder is divided by means of a plurality of centrally orificed partitions into several chambers, and an imperforate piston 33 is slidably fitted within the left-hand chamber on a piston-rod 9. The outwardly-projecting end of said rod is threaded to receive adjustable nuts 12 spaced to seat an orificed finger 8, the latter being terminally engaged in the fork of an arm 7 fixed on a shaft 6 which also carries a shorter arm 5 and a looped end arm 10. A connecting-rod 4 (or a flexible cord) may be connected between the outer end of the shorter arm 5 and the upper end of the trip-arm 3 which shifts the valve-stem 2 of the whistle 1.

Referring to said Fig. 3, the piston-rod 9 is extended to the right of the piston 33 to traverse one orificed bearing in a partition of said cylinder, and carries a valve-head 38 normally kept upon its seat 37 in another spaced orificed partition by reactive resilient traction of a coiled spring 39. A pipe 15, leading to a source of fluid supply under pressure not shown, such as compressed air, communicates through an opening in the wall of said cylinder with the chamber cut off to the left by said partition and valve-seat 37. A by-pass 40 leads from the chamber to the right of the partition 37 to the piston-chamber. Another orificed partition with valve-seat 35 further divides the cylinder into two more chambers, that is, the last-mentioned one to the right of the partition 37 and another to the right of said partition 35. This last-mentioned chamber has communication with the atmosphere by way of an exhaust-port 41. The rod 9 projects through the valve-seat 37, and is terminally contacted by an end of an aligned reciprocating rod 34, being the stem on which another valve-head 36 is mounted, said stem moving through the valve-seat 35, as also through an orifice in the adjacent cylinder-head and being terminally contacted by the adjacent face of the upper end of said lever 13.

Operation. The engineer has only to pull downwardly quickly and sharply the cord 25 by means of said handle 26, which rocks the disk 19 in the direction indicated by the arrow, the projections 21 to 24 in turn rocking upwardly the finger 17 without actuating the lever 13. When the cord 25 is released, the spring 31 is caused to react to return the disk to its initial position, and the projections 24 to 21 successively cause the finger 17 by reason of its engagement with said shoulder 42 to rock the lever 13, causing also the upper end of the lever to push to the left the valve-stem 34 to close the valve-head 36 against its seat 35. The other end of the stem 34 simultaneously pushes the rod 9 to the left

causing the valve-head 38 to be opened away from its seat 37. As compressed air constantly fills the chamber in communication with said pipe 15, the air traverses the open valve-seat to enter the chamber to the right, moving thence through the by-pass 40 into the chamber where it pushes the piston 33 to the left, thus by means of the connections above described, operating the whistle 1. As each projection on the disk releases the finger 17, the tensioned spring 39 in said cylinder is permitted to react to move the rod 9 and seat the valve-head 38 while opening the valve 36. The return of the piston to its initial position thus occasioned forces air through the by-pass and the open valve-seat 35 to be exhausted through the port 41.

It will be observed that the actuation is sharp and immediate, and entirely automatic after release of the cord 25 by the engineer, so that the whistle blasts are clear and definitely terminated, the durations respectively of the blasts and of their intervals being exactly as predetermined. When the engineer desires to cause single or other kinds of signals, this may be effected by pulling downwardly manually the looped arm 10, rocking the arm 3 and operating the whistle.

Having described my invention, what I claim as new, and desire to secure by Letters Patent, is:

1. In combination, a signal, and mechanism operatively connected thereto for initial manual actuation, said mechanism being adapted to actuate the signal in a predetermined succession of timed actuations and intervals, said mechanism including power-relaying means for furnishing to the signal an extraneous power-impulse at a certain stage in the movements of the mechanism.

2. In combination, a signal, and mechanism operatively connected thereto, said mechanism including a manually operable tensionable reaction-device, a valve-controlled device whose movable elements are under compulsion of an auxiliary source of power, an intermediate movable body actuable by said reaction-device only while the latter is in reaction after an initial manual actuation and release to operate said valve-controlled device to initiate a power-impulse from said auxiliary source of power in actuation of the operative connections and said signal, said reaction-device being shaped to move said body at intervals, and said reaction-device also being shaped to prolong each of said actuations and intervals in a predetermined duration.

3. In combination, a signal, a manually movable tensioning reaction-device, and self-setting and re-setting traction-means operated between successive intervals by said reaction-device, and in operative connection with said signal, said traction-means including a power-relaying means operable in com-

municating power impulses to the operative connections at each of said actuations of the traction-means by said reaction-means.

4. In combination, a signal, a manually-operable rock-body having tensioning means adapted to return the rock-body to initial position after operation and release, said rock-body having spaced circumferential projections of predetermined circumferential widths, the interspaces of said projections being of predetermined widths, a rock-lever mounted to have one end moved by said projections only while the reaction-device is reacting after release, a cylinder, a piston reciprocable therein having a rod projecting outwardly therefrom, operating connections between said piston-rod and said signal, said

cylinder containing fluid-receiving and fluid-exhausting chambers, the former under constant communication with a source of fluid supply under pressure, valve-controlled ports in said chambers, valves controlling said ports operable by said piston-rod and by said lever alternately in setting and re-setting, to permit said source of fluid power to relay power impulses to said piston-rod and piston at each action of said lever, and tensioning-means operable on the valves to cause re-setting thereof, after actuation by said reaction rock-body projections of said lever and the release of the lever therefrom.

Signed at Waterloo, Iowa, this 8th day of Nov., 1921.

ALBERTO I. WOODRING.
